UNITED STATES PATENT OFFICE.

ALFRED L. COMTOIS, OF WORCESTER, MASSACHUSETTS, ASSIGNOR TO WOODS-SHERWOOD COMPANY, A CORPORATION OF MASSACHUSETTS.

STRAINER.

1,016,249.

Specification of Letters Patent.

Patented Feb. 6, 1912.

Application filed October 9, 1911. Serial No. 653,584.

To all whom it may concern:

Be it known that I, ALFRED L. COMTOIS, a citizen of the United States, residing at Worcester, in the county of Worcester and State of Massachusetts, have invented a new and useful Strainer, of which the following is a specification.

The principal objects of this invention are to provide a new and improved means for connecting the frame of a strainer with the strainer itself; to provide a connection of this kind of such character that no solder will have to be used in mounting it on the strainer and that its production will be materially simplified so that it can be made chiefly in dies.

The invention also involves other improvements and features of construction as will appear hereinafter.

Reference is to be had to the accompanying drawings in which—

Figure 1 is a side view of an extension strainer constructed in accordance with this invention. Fig. 2 is an end view of the same, and Fig. 3 is a plan.

The invention is shown as applied to an ordinary extension consisting of two members 10 and 11 which are connected by integral eyes 12 at their ends forming guides 30 through which the frames can slide upon each other. It can be applied to other forms of frames however. Mounted on this frame is the strainer 14 which has an upper sheet metal band 15 as usual. The upper band is provided with a top bead 16 integral with the body of the band.

Just under the bead 16 is a wire frame 17 of a general circular form fitting the circumference of the band and resting just 40 under the bead. In order to hold this wire in position without the employment of solder, the sheet metal band is provided with integral projections 18 extending outwardly just under the wire at intervals along the 45 length thereof. The wire is formed of just such shape as to fit the band snugly and the fit of these projections under it effectively holds it in position. This is an exceedingly simple way of securing this result and results in considerable saving in expense as 50 the parts can be made in dies. In fact it adds to the durability of the implement itself.

For the purpose of connecting the strainer 55 with the extension or other frame this wire

17 is provided with integral hooks at opposite sides thereof each hook comprising two parallel spaced outwardly extending arms 20. Each arm extends downwardly to form a vertical member 21 and these members can extend inwardly to form connections 22 which are connected by an integral cross member 23. This cross member 23 preferably is bent on the arc of a circle so as to fit snugly against the circumferential band 15 around the strainer.

It will be seen that a space is provided between the circumferential band and the outwardly extending arms through which the extension frame passes and along which it slides. It will be seen also that the cross bars 23 fitting against the upper band as they do, serve to securely hold the parts in position and increase the rigidity and firmness of the whole construction. At the same time no solder is required, although if solder is applied the device will be further strengthened. In this way there are no internal parts to project on the inside of the strainer and no soldered pieces which are likely to become loose in use. The wire around the top of the strainer serves to strengthen the strainer itself so that the upper metal band can be made of thinner metal and an account of consisting of a single 80 piece of wire surrounding it and integral with the projections for holding the frame, it is of exceedingly firm construction and inexpensive to make and to apply to the strainer. On account of the form and features above described the band 15 and connected parts can be made very rapidly and uniformly in dies.

Although I have illustrated and described a preferred embodiment of the invention, I am aware that modifications can be made therein without departing from the spirit of the invention as expressed in the claims. Therefore, I do not wish to be limited to all the features of construction shown and described, but

What I do claim is:—

1. As an article of manufacture, a strainer comprising an extension frame and the strainer having a wire extending around the upper part thereof and provided with integral projections for receiving and guiding the extension frame.

2. As an article of manufacture, a strainer comprising an extension frame and a

strainer having a pair of opposite guides for the extension frame, each of said guides being formed of a piece of wire having two members spaced apart through which the frame passes, said members being connected by an integral cross piece.

3. As an article of manufacture, a strainer comprising a frame and a strainer having a pair of opposite guides for the frame, each of said guides being formed of a piece of wire having two members spaced apart through which the frame passes, said members being connected by an integral cross piece, said cross piece engaging the wall of the strainer and conforming to the shape thereof.

4. As an article of manufacture, a strainer body having a top band and a wire member connected therewith and provided with a cross piece below the top of the strainer and engaging the outer wall thereof, and two members extending outwardly from the ends of said cross piece and then upwardly substantially to the top of the strainer and then inwardly parallel with each other.

5. As an article of manufacture, a strainer having a metal band and a wire member provided with a cross piece below the top of the band and engaging the outer wall thereof, two members extending outwardly from the end of said cross piece and then upwardly substantially to the top of the

band and then inwardly parallel with each other, said members diverging from each other and extending around the band near the top and being secured thereto solely by contact with the band.

6. As an article of manufacture, a strainer having a top sheet metal band provided with an outwardly extending bead at the top thereof, a wire extending substantially around the band just under said bead and provided on opposite sides of the strainer with integral ways having a passage through them adjacent to the wall of the strainer, the band being provided with projections just under said wire to hold it in place.

7. As an article of manufacture, a strainer having an upper sheet metal band provided with an outwardly extending bead at the top and a wire extending around the strainer itself under the bead, said sheet metal band having extensions on the inside forming projections on the outside just under the wire to hold it in position against the bead.

In testimony whereof I have hereunto set my hand, in the presence of two subscribing witnesses.

ALFRED L. COMTOIS.
